UNITED STATES PATENT OFFICE

SAMUEL GLAUSER PERRIN, OF LE LOCLE, SWITZERLAND, ASSIGNOR, BY MESNE ASSIGNMENTS, TO THE FIRM SCHWAB FRERES & CO., SOCIETE ANONYME, OF LA CHAUX-DE-FONDS, SWITZERLAND, A CORPORATION OF SWITZERLAND

WATCHCASE

Application filed March 21, 1929, Serial No. 348,954, and in Switzerland April 12, 1928.

This invention relates to watchcases and particularly to cases for wrist watches, an object of the invention being to provide a watchcase which normally entirely covers the dial plate of the watch inserted therein. Another object is to provide means on the case for easily and readily uncovering the dial plate in order to see the time.

A practical embodiment of my invention is 10 illustrated in the accompanying drawing wherein:

Fig. 1 is a plan view of the watchcase. Fig. 2 is a section through II—II of Fig. 1. Fig. 3 is a view of the casing from underneath, the bottom cover having been removed.

The watchcase as represented comprises a case body forming the bottom part 1 and a bezel 2 having a rectangular opening 3 provided therein which is adapted to receive a crystal in the grooved edge 11 thereof. To the bezel 2 are hinged in 4 two lids 5 and 6. Each lid has a backwardly extending projection 7 which is subjected to the action of a spring 8. This spring maintains the lids in 20 closed position, in which position they cover the dial plate of the watch. 9 are push levers pivoted on the bezel in 10 and penetrating through the walls thereof to the outside of the case. When these levers are pushed to 25 wards the interior of the watchcase they act on the projections 7 against the springs 8 and turn the lids 5 and 6 into open position.

It will be understood that the invention is not limited to the details of construction as 35 represented in the drawing. Particularly the device for operating the lids could be different. For example there could be provided for each lid a rack sliding in the casing and meshing with a pinion disposed on the axis of 40 rotation of the lids.

I am aware that heretofore it has been proposed to provide a watch case with two hinged lids each provided with a spring tending to close it, which said springs can 45 be simultaneously flexed by a single plunger mounted in the watch case wall. In the construction herein shown and described, however, by the use of separate, oppositely disposed movable members each cooperating 50 with a separate lid, a resistance equivalent to

that of only one spring has to be overcome by the operator in order to open the two lids, each spring serving as the means of transmitting said pressure to the other. This constitutes an improvement over the above mentioned prior construction in which the sum of the resistances of the two springs must be overcome before the two lids can be opened. Obviously, therefore, the same rapidity and 55 positiveness of closure of lids can be attained with my invention upon application by the user of only half the force required to secure the same result in the case of the prior construction.

I claim:

1. A normally closed pocket casing, adapted to contain an article to be alternately disclosed and concealed, comprising, in combination, a substantially flat, hollow body having an opening of relatively considerable area 70 in one face and two oppositely disposed openings in the walls thereof, relatively near the outer edges of the cover plates two cooperating cover plates for said opening hinged adjacent opposite edges thereof, a member 75 located and operatively mounted in each of said smaller openings and operatively connected to one or the other of said cover plates, and spring mechanism normally holding said cover plates in closed position; whereby, 80 when said casing is held between the thumb and fingers of one hand inward pressure thereby exerted on said movable members will open the case.

2. A combination such as defined in claim 85 1 in which said doors are hinged to said casing with the axes of said hinges parallel one to another and extending at right angles to the common line of sliding motion of said movable members.

3. A combination such as described in claim 1 in which said motion transmitting mechanism consists of a lug extending from each door near the hinge thereof, and into the casing interior in the path of one of said 95 movable members.

In testimony whereof I affix my signature.
SAMUEL GLAUSER PERRIN.

CERTIFICATE OF CORRECTION.

Patent No. 1,793,414.

Granted February 17, 1931, to

It is hereby certified that the name of the patentee in the above numbered patent was erroneously written and printed as "Samuel Glauser Perrin" whereas said name should have been written and printed as Samuel Glauser-Perrin, and the name of the assignee should read Schwob Freres & Co., Societe Anonyme, instead of "Schwab Freres & Co., Societe Anonyme", as shown by the records of assignments in this office; and that the said Letters Patent should be read with these corrections therein that the same may conform to the record of the case in the Patent Office.

Signed and sealed this 31st day of March, A. D. 1931.

(Seal)

**M. J. Moore,
Acting Commissioner of Patents.**
